UNITED STATES PATENT OFFICE.

IRA S. DOWNING, OF CLEVELAND, OHIO, ASSIGNOR TO WALTER P. MURPHY, OF CHICAGO, ILLINOIS.

SHEET-METAL CAR END.

1,159,573.

Specification of Letters Patent.

Patented Nov. 9, 1915.

Continuation of application Serial No. 681,784, filed March 5, 1912. This application filed April 7, 1913.
Serial No. 759,424.

To all whom it may concern:

Be it known that I, IRA S. DOWNING, a citizen of the United States, residing at Cleveland, in the county of Cuyahoga and 5 State of Ohio, have invented certain new and useful Improvements in Sheet-Metal Car Ends, of which the following is a specification.

My invention relates to the construction 10 of railway cars, particularly box cars, and has for its primary object to provide a sheet metal end structure for railway cars which will be strong, rigid, durable, and readily attached either to a new car or to an old car 15 to replace a broken or worn end.

The invention has in view, particularly, a sheet metal car end constructed or provided with reinforcing elements or ribs, as they may be generically termed; so disposed that 20 the structure will withstand the peculiar shocks, stresses and pressures exerted against the end of a railway car.

By constructing a car end in accordance with my invention, in the manner to be hereinafter described, it will be at the same time 25 light and very strong and durable.

The invention is shown, in a preferred embodiment, in the accompanying drawing, wherein—

30 Figure 1 is a view in elevation of the end of a railway box car omitting the trucks and certain other parts which are not essential to the understanding of the invention; Fig. 2, a fragmentary sectional plan taken on line 2—2 of Fig. 1; and Fig. 3, a detail sectional view on line 3—3 of Fig. 1.

Like characters of reference designate like parts in the several figures of the drawing.

40 In the drawings, 10 designates the corner posts at one end of the car, 11 the end sill, 12 the outer side sheathing, 13 the inner sheathing, 14 the ridge pole, 15 the purlins, 16 the roof sheets, and 17 the usual end 45 fascia plate.

Referring first to Figs. 1 to 3 inclusive, the end structure is composed of a plurality of metal end sheets, preferably three in number, which extend from top to bottom of 50 the car and are designated 18, 19 and 20, respectively. The outer sheets 18 and 20 are formed on their outer longitudinal edges with angular flanges 21 secured to the corner posts 10 by any suitable means, for ex-

ample, the lag screws 22. Preferably the 55 sheets are provided on their lower edges with inturned flanges 23 which are bolted to the end sill 11. The sheets are formed on their meeting vertical edges with flanges 30 which are riveted one to another as shown. 60

The sheets are preferably formed with 65 pressed ribs or corrugations 29 which are disposed horizontally. With this arrangement any local thrust on the car end, for example the impact which some relatively 70 small, heavy, movable article forming part of the cargo may give against the end when the car is suddenly stopped or started, is taken up by the corrugations and the puncturing or breaking of the end thereby prevented. The thrusts on the horizontal ribs 75 are transmitted to the stiff, vertical ribs formed by flanges 30 which, it will be seen, run from the top to the bottom of the car and are relatively strong and rigid. These vertical ribs serve, in effect, as reinforcing posts intervening between the corner posts of the car, strengthening and rigidifying the end structure and also carrying some of the roof load. 80

Preferably the end sill 11 projects out beyond the end sheets and the vertical ribs or posts formed by the angular flanges on the meeting edges of the sheets are secured to the end sill by angular plates 31. In the 85 construction shown the car has the ordinary end plate, designated 32, to which the upper edges of the sheets are secured by bolts 33. The upper ends of the flanges 30 are capped by cap pieces 34 secured to the end plate by 90 bolts 33 and 35. The fascia plate 17 is notched so that it fits over the cap pieces. Preferably rivets 36 extend through the cap pieces and flanges. The cap pieces, in addition to securely attaching the flanges to 95 the end plate of the car, waterproof the end structure at these points.

While I have described my invention in a preferred embodiment, it will be understood that further modifications might be made 100 without departure from the invention.

I claim:

1. The combination with the framing of a railway car, of a sheet metal end structure comprising a plurality of end sheets 105 extending from top to bottom of the car and provided along their meeting edges with angular flanges which are secured together,

and means for engaging the flanges with the frame members at the top and bottom of the car which provides waterproofing for the upper ends of the flanges.

5 2. The combination with the framing of a railway car, of a sheet metal end structure comprising a plurality of end sheets extending from top to bottom of the car, formed with pressed ribs and provided 10 along their meeting edges with angular flanges which are secured together, and means for engaging the flanges with the frame members at the top and bottom of the car which provides waterproofing for 15 the upper ends of the flanges.

3. The combination with the framing of a railway car, of a sheet metal end structure extending from top to bottom of the car, formed with horizontally disposed pressed 20 ribs and provided along their meeting edges with angular flanges which are secured together, and means for engaging the flanges with the frame members at the top and bottom of the car which provides waterproofing 25 for the upper ends of the flanges.

4. The combination with the framing of a railway car, of a sheet metal end structure comprising a plurality of end sheets extending from top to bottom of the car and 30 provided along their meeting edges with angular flanges which are secured together, and means for engaging the flanges with the frame members at the top and bottom of the car so that said pairs of flanges 35 constitute posts intervening between the corner posts of the car, the upper of said engaging means being formed to waterproof the upper ends of said flanges.

5. The combination with the framing of 40 a railway car, of a sheet metal end structure

comprising a plurality of end sheets extending from top to bottom of the car, formed with horizontally disposed pressed ribs, and provided along their meeting edges with angular flanges which are secured together, and means for engaging said flanges with the frame members at the top and bottom of the car so that said pairs of flanges constitute posts intervening between the corner posts of the car, the upper of said engaging means being formed to waterproof the upper ends of said flanges. 45 50

6. The combination with the framing of a railway car, of a sheet metal end structure comprising a plurality of end sheets extending from top to bottom of the car formed with horizontally disposed pressed ribs and provided along their meeting edges with angular flanges which are secured together, cap pieces over the upper ends of 55 said flanges which are secured to the framing at the top of the car, and angle plates which secure the lower ends of said flanges to the end sill of the car. 60

7. The combination with the framing of a railway car, of a sheet metal end structure comprising a plurality of end sheets extending from top to bottom of the car and provided along their meeting edges with angular flanges which are secured together, cap pieces over the upper ends of 65 said flanges which are secured to the framing at the top of the car, and angle plates which secure the lower ends of said flanges to the end sill of the car. 70
